US0D1070880S

(12) **United States Design Patent** (10) Patent No.: **US D1,070,880 S**
(45) Date of Patent: ** Apr. 15, 2025

(54) **DISPLAY SCREEN OR PORTION THEREOF
WITH A GRAPHICAL USER INTERFACE**

(71) Applicant: **CalmWave, Inc.**, Seattle, WA (US)

(72) Inventors: **Ophir Ronen**, Seattle, WA (US); **Justin Kearns**, Lexington, KY (US); **Michael Gruzynski**, Seattle, WA (US); **Keith Boudreau**, Durham, NC (US); **Christian Bauer**, Frisco, TX (US); **Margaret Pilon**, Seattle, WA (US)

(73) Assignee: **CALMWAVE, INC.**, Seattle, WA (US)

(**) Term: **15 Years**

(21) Appl. No.: **29/879,405**

(22) Filed: **Jul. 7, 2023**

(51) LOC (15) Cl. 14-04
(52) U.S. Cl. USPC **D14/485**

(57) **CLAIM**

The ornamental design for a display screen or portion thereof with a graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with a graphical user interface showing the claimed design.

The broken lines are included for the purpose of illustrating portions of the display screen or portion thereof with a graphical user interface that form no part of the claimed design.

**1 Claim, 1 Drawing Sheet
(1 of 1 Drawing Sheet(s) Filed in Color)**
